CHRISTIAN N. SMITH, OF ELGIN, ILLINOIS.

MACHINE FOR MAKING METALLIC PRINTING-PLATES.

1,297,266.

Specification of Letters Patent. Patented Mar. 11, 1919.

Application filed May 24, 1917. Serial No. 170,669.

To all whom it may concern:

Be it known that I, CHRISTIAN N. SMITH, a citizen of the United States, residing in Elgin, in the county of Kane and State of Illinois, have invented certain new and useful Improvements in Machines for Making Metallic Printing Plates.

My invention relates to an improved mechanism or apparatus suitable for use in making metallic printing plates in accordance with my improved process and invention.

Subject matter of invention herein described and shown, but not claimed will be found shown, described and claimed in a co-pending application Serial No. 260,408, filed by me and in my name October 30, 1918, for process of making metallic printing plates, the same being a division of this application.

The principal object of this invention is to provide a simple, economical and efficient process of making metallic printing plates, either flat, or of curved or semi-cylindrical form, comprising a metallic shell, such as an electrotype shell, having a backing of suitable metal cast in contact with such shell. Other and further objects of the invention will appear from the following description and claims, and from an inspection of the drawings, which are made a part hereof.

The invention consists in the improved process of making metallic printing plates, and in the improved mechanism or apparatus for use in practising my improved process, and in the features, combinations, parts and details of construction herein described and claimed.

In the accompanying drawings, Figure 1 is a plan view of a mechanism or apparatus for making metallic printing plates by and in accordance with my improved process and invention;

Fig. 2, a view in side elevation of the device shown in Fig. 1, showing the curved or semi-cylindrical mold with its heating chamber in lowered or horizontal position and with the mold closed or in position to form a curved molding chamber;

Fig. 3, a view in vertical horizontal section taken on line 3, 3, of Fig. 2, looking in the direction of the arrow, with the upper or inner mold member shown in open position in broken lines;

Fig. 4, an enlarged detail sectional view taken on line 4, 4, of Fig. 2, and showing

in transverse section the portion of the mold chamber and the relatively movable mold members forming the curved mold chamber, with an electrotype shell or curved type 60 plate in position in the curved mold chamber, and with a curved flexible metallic plate removably mounted in the mold chamber and in contact with the back face of the electrotype shell;

Fig. 5, an enlarged detail view in longitudinal section taken through the center of the outer or lower mold member on line 5, 5, of Fig. 3, looking in the direction of the arrow, with a portion of such mold member broken 70 away;

Fig. 6, a view in central longitudinal section, taken on line 6, of Fig. 1, looking in the direction of the arrow, but with the mold members which form the curved mold chamber in raised or vertical position, and with the mold chamber provided with an electrotype plate in position therein, and a flexible metallic plate, removably arranged in position to engage the curved back surface 80 of the electrotype plate and cause the latter to be held in contact with the curved concave or inner surface or concave wall of the mold chamber;

Fig. 7, an enlarged detail view in longitudinal section, taken on the same line as Fig. 6, and showing the electrotype plate or shell in contact with the surface of the concave wall of the mold chamber, and with the flexible metallic plate, which is in contact with 90 the back face of the electrotype shell, partially raised or partially withdrawn from the mold chamber, and with the molten metal for forming the backing in contact with the back of the electrotype shell below 95 the bottom edge of the partially removed flexible plate;

Fig. 8, a fragmentary detail view of a portion of an electrotype shell, having a make ready overlay of chalk or similar material on its printing surface;

Fig. 9, an enlarged detail view in transverse vertical section, taken on line 9, of Fig. 7, looking in the direction of the arrow, and showing the electrotype shell in the 105 mold chamber with a make ready overlay in contact with the printing surface of the shell, and with the flexible metallic sheet in contact with the back of the electrotype shell, before the operation of pouring in the 110 molten metal;

Fig. 10, a similar enlarged detail sectional

view, showing the electrotype plate and the make ready overlay in the mold and pressed tightly in contact with the concave surface of the curved mold by the metal poured into the mold and allowed to come into contact with the shell upon the removal of the flexible sheet of metal; and

Fig. 11, a view in elevation of a device for making flat metallic printing plates in accordance with my invention and improvements, a portion of the upper and lower pivotally connected mold members being broken away, to show the mold chamber adapted to contain an electrotype shell and removable flexible barrier plate or sheet, said figure also showing the heating chambers and burners for heating the mold chamber.

In constructing a mechanism in accordance with my invention and improvements and suitable for use in practising my improved process of making metallic printing plates, I provide a main frame 1, having uprights 2, 2, provided with bearings 3, 3, in the upper extremities of said uprights. The side frame members thus formed are connected by means of transverse frame members 4 and 5.

A pair of main mold members, comprising a lower or outer mold member 6, and an upper or inner mold member 7 adapted to form a mold chamber 8 therebetween, which chamber is semi-cylindrical in form, is provided and mounted in the main frame in such a manner as to permit the mold chamber to be opened and closed, and to permit the movement of the connected upper and lower mold members 7 and 6 to raised and lowered positions alternately, as desired. The lower or outer mold member 6 is provided with trunnions or stub shafts 9 which project outward laterally in opposite directions on opposite sides of said mold member and are journaled in the bearings 3 in the upright frame members 2. (See Figs. 1, 2 and 3).

The upper or inner mold member 7 is pivotally connected in operative engagement with the lower mold member 6 by means of hinge members 10 on the upper mold member, hinge members 11 on the lower mold member, and pintles or horizontal pivots 12, which connect said hinge members 10 and 11 in such a manner as to permit the upper mold member to swing into position to open and close the mold chamber as desired. The upper mold member 7 is shown in closed or mold chamber-forming position in full lines in Fig. 3, and is shown in broken lines in said figure in the position which it would occupy when the mold chamber is open, or in position to permit the removal of a printing plate upon the completion of the process of making the same, and to permit the insertion of a metallic electrotype shell into position in the mold chamber, and the placing of the

flexible barrier sheet hereinafter described, in position.

A curved marginal gage bar 13 is mounted in position to form an end marginal wall of the mold chamber; and straight marginal gage bars 14, 14, are removably mounted in position to form removable side marginal walls of the mold chamber. The curved end marginal gage bar is removably supported in operative position upon the lower mold member 6, by means of studs 15, 15, which are anchored in the lower mold member 6, and sockets or slots 16, 16, in the gage bar 13, which are adapted to admit and engage the studs 15 when the gage bar is in position to form the removable end wall of the mold chamber. The end gage bar 13 is provided with grooves or dovetailed mortises 17, at or near its opposite extremity, and each of the gage bars 14 is provided with an endwise projecting tongue or tenon 18 adapted to fit snugly, but removably, in the corresponding groove 17. Each gage bar 14 is also provided with one or more studs 19, each of which is adapted to be removably inserted in a corresponding recess 20 in the mold member 6. The studs 19 are, by preference, tapered, and the apertures 20 are similarly tapered. The gage bars 14 are provided with marginal recesses 21 on the inner sides thereof and adjacent to semi-circular wall 22 formed by the lower or outer mold member 6. These recesses open inward or in the direction of the interior of the mold chamber 23 and are adapted to engage the edges or margins 24 of a flexible metallic barrier plate 25, which is removably mounted in the mold chamber, with its margins in sliding engagement with the grooved gage bars 14, and with its curved or end margin 26 movable into and out of position to be engaged by the longitudinal groove 27 in the curved gage bar 13. (See Figs. 4, 5, 6 and 7, and also Fig. 3.)

The lower mold member 6 is provided with an outer wall 28, which is located on the outside of the lower inner mold chamber wall formed by said mold member 6, and is provided with a space 30 between said lower inner wall and said outer wall and forming a heating chamber adapted to enable the mold member 6 and the outer wall of the mold chamber to be heated in an efficient manner. The outer wall 28 of the heating chamber is provided with strengthening ribs 31 on the outside of said wall; and strengthening ribs 32, located on the inside of the wall, are also provided. The upper or inner mold member 7 is also, by preference, provided with a heating chamber 33, the outer wall of which is formed by a curved wall portion 34 of said inner or upper mold member 7. Ribs 35, which may be integral with the wall 34, and inner ribs 36 between the heating chamber wall 34 and the mold cham-

ber wall 37, serve to brace and strengthen the inner mold member 7.

Securing means is provided for securing the upper and lower mold members 6 and 7 in mold chamber-forming position. The securing means for this purpose, when constructed as shown in the drawings, may consist of a plurality of laterally projecting lugs or clamping members 38 upon and in rigid relation to the marginal portion of the upper mold member 7, and clamping screws 39, pivotally connected with the adjacent margin of the lower mold member 6, by means of lugs 40 and bolts 41, and having clamping nuts 42 mounted in threaded engagement with the said clamping screws, respectively, and adapted to be screwed into and out of securing engagement with the clamping members 38, respectively, when the screws are moved into position to extend into recesses 43 in the clamping members 38.

Laterally projecting bosses 44 are provided, which are, by preference, integral with the marginal portion of the upper mold member 7, and a shaft or axle 45 is rotatively mounted in these bosses in position to extend over the adjacent marginal portion of the lower mold member 6, and one or more eccentrics or cams 46 are mounted upon, and, by preference, in fixed relation to and adapted to rotate with said shaft, and in sliding engagement with the adjacent marginal surface of the mold member 6. One or more handles or levers 47 are mounted in fixed relation to the shaft and eccentric mechanism, for operating the same to raise the upper mold member 7 with respect to the lower mold member 6 in opening the mold chamber. When the lever and eccentric mechanism is in the position shown in Fig. 3, the mold chamber walls are in parallel relation, or in the position which they should occupy during the operation of casting. It is obvious that by turning the eccentric and lever mechanism downward in the direction indicated by the arrow in Fig. 3, the upper mold member 7 will be raised with respect to the mold member 6, to a sufficient extent to release the upper mold member from engagement with the casting contained in the mold chamber upon the completion of the operation of casting a printing plate in the chamber.

Means is provided for supporting the pivoted mold, comprising mold members 6 and 7 in horizontal or lowered position, as shown in Figs. 2 and 3, and in vertical or raised position, as shown in Fig. 6, and suitable means for heating both of said mold members, and means for cooling the mold, all adapted to enable the mold to be swung to lowered or horizontal position and to raised or vertical position, and to be opened and closed with facility. A trip lever 48 is

pivotedly mounted upon the main frame by means of a transverse shaft 49 to which the lever is fixed by means of a set screw 50, or other suitable securing means; and one or more stop arms 51 are secured in fixed relation to the rock shaft 49 in position to move into and out of supporting engagement with shoulders 52 on the lower mold member 6. (See Figs. 2 and 3). Bosses or shoulders 53 near the opposite extremity of the mold member 6 are adapted to rest upon the transverse frame member 4 when the mold is in horizontal position. It is plain that the raising of the lever 48 will release the stop arms 51 from engagement with bosses 52 and permit the pivoted mold to be swung from horizontal position, as shown in Fig. 2, to vertical or raised position, as shown in Fig. 6. A handle 54 upon the end of the mold member 6 is used for raising and lowering the mold. The means for heating the heating chambers 30 and 33, and thereby heating the mold chamber and its contents, when constructed as shown in the drawings, comprises a plurality of Bunsen burners 55 mounted in position to discharge heated gas into the heating chamber 30 of the mold member 6. These burners are connected with a source of gas or fuel supply by means of a pipe or conduit 56 and a flexible pipe or conduit 57, adapted to permit the movement of the mold without disturbing the connection with the fuel supply. Controlling cocks or valves 58, which may be of any ordinary, desired, or well known form, are mounted in position to control the supply of fuel to the burners 55. Burners 59, which may be in the form of ordinary Bunsen burners, are mounted in position to communicate with and heat the heating chamber 33, and are connected with a source of fuel or gas supply by means of a fuel supply pipe or conduit 60, which communicates with a conduit 61, which is, by preference, in the form of a flexible pipe, and is adapted to be connected with a gas tank or main, or other suitable source of fuel supply, and to permit the movement of the mold with the Bunsen burners attached. Controlling cocks or valves 62, are mounted in position to control the supply of gas or fuel to the burners 59. A set of burners 63 is also provided and mounted, by preference, in such position that they will be directly beneath the upper mold member 7 when the mold is open, and said upper mold member is swung away from the lower mold member 6 to open horizontal position, as shown in broken lines in Fig. 3. These burners 63 may be in the form of Bunsen burners of any desired, suitable well known type, and may be stationary, and are connected with a fuel supply conduit or pipe 64, which is adapted to be

connected with a gas supply pipe 65 leading to a suitable source of fuel supply. It is obvious that the burners 55 attached to the mold member 6 are adapted to heat the heating chamber 30 and the walls of the mold chamber in an efficient manner, and to enable stationary burners arranged beneath the mold member 6 to be dispensed with.

10 In order to provide means for cooling the mold chamber and mold quickly and in an efficient manner nozzles 66, 66, are mounted in position to discharge cold air into the heating chamber 30, and are connected with a suitable source of air supply by means of pipes 67 and 68, which may be in the form of flexible pipes, or rubber tubing; and one or more air nozzles 69, which may be stationary, are mounted in position to discharge cold air into the heating chamber 33 of the upper mold member 7 through an opening or openings 70. The nozzle or nozzles 69 are connected with an air pipe or conduit 71, which is adapted to communicate with a suitable source of air supply. The stationary nozzles 69 are adapted to enable cool air to be introduced into the chamber 33 when the mold is in vertical position. (See Fig. 6.)

30 The chamber 33 is provided with a suitable number of vents or outlets 72, at its upper extremity, and the heating chamber 30 is also provided with similar outlet passages 73 at its upper extremity.

35 In Fig. 11 is shown a mechanism for use in the practice of my improved process of making flat metallic printing plates, and comprises an upper mold member 74 and a lower mold member 75 operatively connected by means of hinges 76, having pintles 77. The upper mold member forms one wall 78 of a flat mold chamber, and the lower mold member 75 forms the other wall 79 of the mold chamber 80. Gage bars 81, 40 82 and 83 are removably mounted in position to form the marginal walls of the mold chamber and are provided with longitudinal inner grooves 89 which are adapted to engage and hold removably in position in the mold chamber a flexible barrier plate 84, which is, by preference, formed of sheet metal and is adapted to engage and cover the entire back surface of a metallic electrotype shell, when such shell 83 is placed in 45 position in the mold chamber, and to enable the barrier plate to be pressed against such electrotype shell by molten metal introduced into the mold chamber. And the barrier plate or sheet 83 is adapted to be removed from the chamber and from between the molten metal and the electrotype shell, when the mold, and the electrotype shell and barrier plate are in raised or vertical position, by gradually raising the barrier plate and permitting the molten metal to flow be-

neath the bottom edge of the barrier plate and into uniting contact with the electrotype shell, during the operation of gradually raising and removing the barrier plate edge-wise from the mold.

70 Suitable means is provided for connecting the mold members 74 and 75, which may consist of one or more clamps having clamping jaws 85, pivoted to the lower mold member by means of pivots 86 and lugs 87 and 75 having clamping screws 88, for engaging and securing the upper mold member in closed or mold chamber-forming position. The lower mold members 75 has trunnions 89 fixed thereto and journaled in suitable bearings in supporting frame members 90. The mold member 75 has a heating chamber 91 and the upper mold member 74 has a heating chamber 92. The heating chamber 91 has openings 93 in the bottom of said chamber and the heating chamber 92 has openings 94 in its bottom end, and both of said chambers are provided with vents or outlet openings 95 at their upper extremities. A set of burners 96 is provided, which may be in the form of a suitable number of ordinary Bunsen burners, or any suitable known type, which may be connected with a gas supply pipe or conduit 97, mounted in position to communicate with a suitable gas supply conduit 98, adapted to be connected with a source of gas supply. One or more air nozzles 99 are mounted in position to discharge cool air into the chambers 91 and 92, respectively, and are connected with a source 100 of air supply by means of a conduit 100, or in any suitable, ordinary and well known manner.

105 In practising my improved process of making metallic printing plates, I provide a metallic electrotype shell 101 which is made in the usual and ordinary manner in common practice and well known to those skilled in the art to which this invention relates. It is therefore deemed unnecessary 110 to describe the process or method of making such electrotype shells or plates in detail herein.

115 The electrotype shell is placed in the mold chamber with the printing face, or face on which the type characters are located, in contact with the mold chamber wall formed by the lower mold member. When the metallic printing plate to be made is to be in curved or semi-cylindrical form, the mold chamber is of curved or semi-cylindrical form, as shown in Figs. 1 to 7 inclusive, and the electrotype shell is placed in contact with the concave surface of the lower mold chamber wall, as shown in Figs. 4, 6 and 7. The 120 flexible metallic barrier plate or sheet 25 is placed in the mold chamber in contact with the back of the electrotype shell, and in position to entirely cover the back of the shell. The margins or edges of the metallic 125 130

barrier sheet are mounted in sliding engagement with the longitudinal slots 21 of the side gage bars 14; and the bottom edge of said sheet extends into the curved slot in the bottom of the curved gage bar 13 as already suggested. The mold chamber is then closed by swinging the top mold member 7,—which has, by preference, been previously heated,—into mold chamber-forming position, as shown in Figs. 1, 2 and 4, and in full lines in Fig. 3. The mold members are then clamped together, and the bottom mold member, having also been previously heated, the mold is tipped from horizontal position to vertical position, in which position it is shown in Fig. 6. The mold chamber and also the flexible metallic barrier sheet 25, and electrotype shell 101 are thus in vertical position, and the barrier plate, which covers the entire back surface of the electrotype shell is in position to permit molten metal to be introduced into the mold chamber between the barrier sheet 25 and the mold chamber wall formed by the upper mold member. Molten metal suitable for forming a backing for the electrotype shell,—which shell is usually of copper and has, of course, been previously tinned, or covered on the back with a coating of tin,—is introduced into the mold chamber, filling the chamber back of the barrier plate, and pressing the flexible barrier plate snugly against the back of the electrotype shell. It should be noted that the metallic barrier plate and electrotype shell should be thoroughly heated and are in fact thoroughly heated when the mold chamber walls are heated, and previously to pouring the molten metal. The flexible barrier plate having thus been forced into snugly fitting contact with the electrotype shell by the action of the heavy molten metal, the flexible barrier plate is withdrawn gradually from the mold chamber and from between the molten metal and the electrotype shell, by gradually raising the flexible barrier plate, while the plate and shell are in vertical position. During the operation of raising or withdrawing the flexible barrier plate, the molten metal comes gradually and progressively into contact with the back of the tinned electrotype shell and below the bottom edge of the upwardly moving flexible barrier plate. The portion of the electrotype shell which is engaged by the barrier sheet during the operation of raising the barrier sheet is thus held evenly and uniformly in contact with the mold chamber wall by the weight of the molten metal back of the barrier sheet, and as the barrier sheet is raised the molten metal below the lower edge of the barrier sheet comes in contact with the heated tinned back surface of the electrotype shell and unites with the electrotype shell progressively as the barrier

plate is raised, and with the shell forms a complete metallic printing plate which is in one integral piece, and which has an even and uniform printing surface of exactly the desired curvature or cylindrical form required for its use in the operation of printing. 70

The mold having been heated to the proper temperature to enable the molten metal to flow freely and unite with the heated tinned surface of the electrotype shell, the burners are lowered or extinguished, if desired, either before or immediately following the raising of the mold to vertical position, and the introduction of the molten metal for 80 forming the backing for the electrotype shell. After removing the flexible barrier sheet, it is desirable to cool the mold quickly, in order to enable the casting or metallic printing plate to be removed without unnecessary loss of time. This is accomplished in a simple and efficient manner by simply introducing cold air into the heating chamber through the air nozzles above described. I contemplate cooling the mold 85 chamber by any ordinary and well known cooling means, but prefer to introduce cooling means in the form of a fluid, such as air or water, into the heating chambers or in contact with the outside of the mold 90 chamber walls. 95

In practice it is desirable to detachably connect the electrotype shell with the flexible barrier sheet in such a manner as to insure the holding of the electrotype shell in exactly 100 the proper position in the mold chamber to obtain the desired curvature without destroying or interfering with the proper registration of the plate or the characters and figures, and highlights and "solids" with 105 those of other printing plates in connection with which such printing plate is to be used, for instance, in color printing. In order to accomplish this in a simple and efficient manner, when required, I detachably connect the electrotype shell with the metallic barrier sheet at two or more points by means of a drop of solder 102, soldered to the electrotype shell and barrier plate at a suitable point or points to detachably connect them. 110 A drop of solder near the bottom extremity, and another near the top extremity of the shell and barrier sheet, as indicated in Fig. 4, is sufficient to serve the purpose. The solder should be so placed that it will be 115 melted by the molten metal poured into the mold, in forming the backing for the printing plate.

In order to indent the printing surface of the electrotype shell or printing plate in a 125 simple and efficient manner, in connection with the practice of my improved process, it is only necessary to place a make-ready overlay 103, which may be in the form of a coating or thin layer of chalk, or other suit- 130

able material, for making an overlay, in the desired position upon the printing surface of the electrotype shell. (See Figs. 8, 9 and 10.) This is of course done before placing the electrotype shell in the mold chamber.

The pouring in of the molten metal with the inlay in the position in which it is shown in Fig. 9, and the withdrawing of the flexible barrier plate so as to permit the molten metal to come into uniting contact with the back of the electrotype shell, will cause the electrotype shell to be pressed against the face of the wall of the mold, as shown in Fig. 10, leaving the desired indentation corresponding with the shape and position of the overlay or overlaid material 103, as indicated in Fig. 10.

The electrotype shells or type plates used in making metallic printing plates in accordance with my invention, are usually of copper, or copper and other suitable metal, such for instance, as nickel, the copper shell being formed in the ordinary or any desired suitable known manner, by depositing the copper or metal upon a mold arranged in an electrolytic bath containing suitable chemicals, and embraced within an electric circuit. The electrotype shell is tinned in the usual manner well known in the art. The metal which forms the metallic backing for the electrotype shell should be softer than copper, or should have a lower melting point than that of the copper or metal of which the electrotype shell is formed. A metallic compound or alloy containing approximately 92% lead; 4% tin, and 4% antimony is suitable for the purpose, and has been found in practice to give entirely satisfactory results.

40 I claim:

1. In a mechanism of the class described, the combination of a mold forming a mold chamber adapted to contain a metallic electrotype shell, a flexible barrier plate removably mounted in the mold chamber in position to engage and cover the entire back surface of the electrotype shell when such shell is in position in the chamber, means for removably holding the flexible barrier plate in the chamber and in engagement with the electrotype shell, and in position to enable molten metal to be introduced into said chamber and in contact with the flexible barrier plate, and means for heating the mold chamber.

2. In a mechanism of the class described, the combination of a plurality of mold members adapted to form a mold chamber, a flexible barrier sheet removably mounted in the mold chamber in position to engage and cover the back surface of an electrotype shell to be contained in such chamber, means for removably holding the flexible barrier sheet in the chamber in position to engage and cover the back surface of such electro-

type shell and adapted to enable molten metal to be introduced into said chamber and in contact with the flexible barrier sheet, means for operatively connecting the mold members, and means for heating the mold chamber.

3. In a mechanism of the class described, the combination of a plurality of relatively movable mold members forming a mold chamber adapted to contain an electrotype shell, a flexible metallic sheet removably mounted in the mold chamber in position to engage and cover the back surface of such electrotype shell to be contained in such chamber, means for removably holding said flexible metallic sheet in operative position in the chamber and in position to engage and cover the back surface of such electrotype shell, and adapted to permit the introduction of molten metal into said chamber and in contact with the flexible metallic sheet, means for operatively connecting said relatively movable mold members, and means for heating the mold chamber.

4. In a mechanism of the class described, the combination of a plurality of relatively movable mold members forming a mold chamber adapted to contain an electrotype shell, each of said mold members being provided with means for heating a wall of such mold chamber, a frame upon which said mold members are pivotally mounted, a flexible metallic barrier sheet removably mounted in the mold chamber in position to engage and cover the back surface of such electrotype shell to be contained in the chamber, means for removably holding said flexible metallic barrier sheet in the chamber and in position to engage and cover the back surface of such electrotype shell, and adapted to permit the introduction of molten metal into the mold chamber in position to engage and press the removable barrier sheet against the surface of such electrotype shell, and means for operatively connecting said relatively movable mold members.

5. In a mechanism of the class described, the combination of a plurality of relatively movable mold members forming a mold chamber having curved walls and adapted to contain a curved electrotype shell, a flexible metallic sheet bent into curved form and removably mounted in the mold chamber in position to engage and cover the back surface of such electrotype shell to be contained in such chamber, means for removable holding such curved flexible metallic sheet in position to engage and cover the back surface of such electrotype shell and in position to admit molten metal into said chamber in contact with the flexible metallic sheet, means for operatively connecting said relatively movable mold members, and means for heating the mold chamber.

6. In a mechanism of the class described,

- the combination of a plurality of relatively movable mold members forming a mold chamber having curved walls and adapted to contain a curved electrotype shell, a 5 curved flexible metallic sheet adapted to be removably mounted in the mold chamber in position to engage and cover the back surface of such electrotype shell to be contained in said chamber, gage bars removably mounted in position to form marginal walls of said chamber and adapted to hold such curved flexible metallic sheet removably in position to engage and cover the back surface of such electrotype shell, and adapted 10 to admit molten metal into said chamber in contact with the flexible metallic sheet, means for operatively connecting said relatively movable mold members, and means for heating the mold chamber. 15 7. In a mechanism of the class described, the combination of a plurality of relatively movable mold members forming a semi-cylindrical mold chamber adapted to contain a curved electrotype shell, means for 20 pivotally supporting said mold members, a flexible barrier sheet bent into semi-cylindrical form and removably mounted in the mold chamber in position to engage and cover the back surface of such electrotype shell, marginal gage bars removably mounted in position to form marginal walls of said chamber and adapted to engage the margins of the flexible barrier sheet, for removably holding said flexible sheet in operative position in the mold chamber and in removable engagement with the electrotype shell, means for heating the mold chamber, said heating means being adapted to permit the movement of the connected upper and lower mold members to raised and lowered positions alternately, and means for cooling the mold chamber. 25 30 35 Signed at Chicago, Illinois, this 17th day of May, 1917.
